[57] ABSTRACT

A spray system for use in a rolling mill comprises a carriage assembly mounted on linear bearings for movement along an X-axis parallel to an horizontal line passing through the bite of two superposed work rolls, two spray manifolds mounted on the carriage assembly along a Y-axis parallel to a vertical centerline passing through the work rolls, each manifold containing at least one spray nozzle for setting a predetermined spray pattern on each work roll, a carriage traverse mechanism for adjusting the traverse position of the carriage assembly along the X-axis, and two manifold lift mechanisms mounted on the carriage assembly to independently adjust the position of each spray manifold along the Y-axis.

3 Claims, 1 Drawing Sheet

SPRAY SYSTEM FOR ROLLING MILL

This invention relates to a spray system for use in all types of rolling mills.

It is common practice in rolling mills, more particularly in aluminum rolling mills, to apply an oil or water based coolant or lubricant to the work rolls to control shape of the rolled sheet and to prevent sticking of the aluminum sheet to the rolls. The coolant or lubricant is normally applied in the form of coolant sprays of various capacities and pattern geometries using one or more spray nozzles per zone widths in the range but not limited to 55 mm, mounted at predetermined locations with respect to each roll. Upon initial design of the spray system, an optimum spray pattern is conceived based upon the application. This optimum spray pattern determines an X and Y position where the spray nozzle or nozzles must be located within the aluminum rolling mill with respect to the geometric position of the roll surfaces. 10

X and Y position references are initially established with respect to the optimum spray pattern and the maximum roll diameters. As the roll diameters and position of the strip change within the rolling mill, the X and Y coordinates of the spray manifolds are changed by operation of the traverse and lift mechanisms. 15

Since the roll stack centerline is at a fixed X location

within the rolling mill, a single traverse mechanism 18 is used to move the X coordinates of both spray manifolds

10 and 12 mounted on carriage assembly 14 with respect to the stack centerline. At the optimum X location from the geometric roll surface, thickness shims are inserted

in shim area 30 between the traverse mechanism and the carriage assembly to set the position of the carriage assembly. 20

The Y position of the strip within the rolling mill can vary due to diametrical grind-down and subsequent

stack shimming of the backup and work rolls. Because

of this, the Y position of the top work roll and bottom

work roll manifolds 10 and 12 must be controlled inde- 25

pendently. Thickness shims are inserted in shim areas 32 and 34 between the lift mechanisms 26 and 28 and the

roll manifolds 10 and 12 to set the position of the mani- 30

folds. 35

Although mechanical thickness shims are disclosed

for setting the position of the carriage assembly or the

position of the manifolds, it is to be understood that

other means such as hydraulic or electrical servo con- 40

trols could be used for that purpose.

Although the direction of movement of the strip is

shown as left to right, it is to be understood that the

spray system in accordance with the invention could

45 apply to a reversing mill or to exit sprays on a single stand or tandem mill.

Although the invention has been disclosed with refer- 40

ence to a preferred embodiment, it is to be understood

that the invention is not limited to such embodiment and

50 that other alternatives are also envisaged within the scope of the following claims.

I claim:

1. A spray system for use in a rolling mill comprising two superposed work rolls between which is defined a bit through which passes a metal strip to be rolled, said spray system comprising:

(a) a carriage assembly mounted on linear bearings for movement along an X-axis parallel to an horizontal line passing through the bite of the two superposed work rolls;

(b) two spray manifolds mounted on said carriage assembly along a Y-axis parallel to a vertical centerline passing through the work rolls, each manifold containing at least one spray nozzle for setting a predetermined spray pattern on each work roll;

(c) a carriage traverse mechanism for adjusting the traverse position of the carriage assembly along said X-axis; and

ing the position of each spray manifold along a Y-axis parallel to the vertical centerline of the work rolls.

The spray manifolds 10 and 12 are each set at a predetermined X and Y coordinate within the aluminum rolling mill in order to precisely locate the positions of the spray nozzles with respect to the surfaces of the work rolls 22. Upon initial design of the spray system, an optimum spray pattern is conceived based upon the application. This optimum spray pattern determines an X and Y position where the spray nozzle or nozzles must be located within the aluminum rolling mill with respect to the geometric position of the roll surfaces.

X and Y position references are initially established with respect to the optimum spray pattern and the maximum roll diameters. As the roll diameters and position of the strip change within the rolling mill, the X and Y coordinates of the spray manifolds are changed by operation of the traverse and lift mechanisms.

Since the roll stack centerline is at a fixed X location within the rolling mill, a single traverse mechanism 18 is used to move the X coordinates of both spray manifolds 10 and 12 mounted on carriage assembly 14 with respect to the stack centerline. At the optimum X location from the geometric roll surface, thickness shims are inserted in shim area 30 between the traverse mechanism and the carriage assembly to set the position of the carriage assembly.

The Y position of the strip within the rolling mill can vary due to diametrical grind-down and subsequent stack shimming of the backup and work rolls. Because of this, the Y position of the top work roll and bottom work roll manifolds 10 and 12 must be controlled independently. Thickness shims are inserted in shim areas 32 and 34 between the lift mechanisms 26 and 28 and the roll manifolds 10 and 12 to set the position of the manifolds.

Although mechanical thickness shims are disclosed for setting the position of the carriage assembly or the position of the manifolds, it is to be understood that other means such as hydraulic or electrical servo controls could be used for that purpose.

Although the direction of movement of the strip is shown as left to right, it is to be understood that the spray system in accordance with the invention could apply to a reversing mill or to exit sprays on a single stand or tandem mill.

Although the invention has been disclosed with reference to a preferred embodiment, it is to be understood that the invention is not limited to such embodiment and that other alternatives are also envisaged within the scope of the following claims.

I claim:

1. A spray system for use in a rolling mill comprising two superposed work rolls between which is defined a bit through which passes a metal strip to be rolled, said spray system comprising:

(a) a carriage assembly mounted on linear bearings for movement along an X-axis parallel to an horizontal line passing through the bite of the two superposed work rolls;

(b) two spray manifolds mounted on said carriage assembly along a Y-axis parallel to a vertical centerline passing through the work rolls, each manifold containing at least one spray nozzle for setting a predetermined spray pattern on each work roll;

(c) a carriage traverse mechanism for adjusting the traverse position of the carriage assembly along said X-axis; and

- (d) two manifold lift mechanisms mounted on the carriage assembly to independently adjust the position of each spray manifold along said Y-axis.
2. A spray system as defined in claim 2, wherein adjustment shims are provided between said traverse

mechanism and said carriage assembly to set the traverse position of the carriage assembly.

- 5 3. A spray system as defined in claim 1 wherein adjustment shims are provided between each lift mechanism and the associated spray manifold to set the position of the spray manifolds.
